INVENTOR
GEORGE H. GIBSON
BY
John E. Gubbell
his ATTORNEY

UNITED STATES PATENT OFFICE.

GEORGE H. GIBSON, OF MONTCLAIR, NEW JERSEY.

COMBUSTION CONTROL.

Application filed August 22, 1922. Serial No. 583,491.

To all whom it may concern:

Be it known that I, GEORGE H. GIBSON, a citizen of the United States, and resident of Montclair, New Jersey, in the county of Essex and State of New Jersey, have invented certain new and useful Improvements in Combustion Controls, of which the following is a specification.

The general object of the present invention is to provide improved apparatus for regulating combustion in furnaces heated by the combustion of solid fuel, and my invention comprises simple and effective means for automatically regulating the supply of fuel to the furnace grate as required to maintain the fuel bed resistance to gas flow therethrough approximately constant.

The various features of novelty which characterize my invention are pointed out with particularity in the claims annexed to and forming a part of this specification. For a better understanding of the invention, advantages possessed by it, and various specific objects attained with it, reference should be had to the accompanying drawings and descriptive matter in which I have illustrated and described preferred forms of embodiment of the invention.

Of the drawings:

Fig. 1 is a sectional elevation of a portion of a locomotive in which my invention is embodied;

Fig. 2 is a sectional elevation of a portion of the control mechanism employed in Fig. 1; and

Fig. 3 is a diagrammatic representation of a modification of the apparatus shown in Fig. 1.

In the drawings, and referring first to the construction shown in Figs. 1 and 2, A represents a locomotive of which A' is the grate, A² the firebox, A³ the smoke box, A⁴ the primary air inlet to the ash pit, A⁵ the smokestack, A⁶ the steam dome, A⁷ the steam pipe leading from the steam dome to the valve chest A⁸, of the locomotive, and A⁹ the secondary air inlet. The exhaust pipe A¹⁰ leads from the valve chest to an exhaust nozzle B discharging axially through the smoke stack A⁵ as is usual. A bellows pressure chamber C has its interior connected by a pipe C' to steam pipe A⁷, and has its movable lower end connected to the stem of a needle valve D which throttles the outlet of the exhaust nozzle B more

or less, in inverse relation to the locomotive steam pressure. Fuel is fed on to the grate A' by an automatic stoker mechanism E at a rate regulated by the valve F' controlling the flow of steam through the pipe F from the steam dome of the locomotive to the steam motor E' driving the stoker mechanism.

The extent to which the valve F' is opened, and consequently the rate at which fuel is fed on to the grate A', is controlled by a pressure motor G, and the means provided for regulating the pressure therein. The pressure regulating means is a differential pressure device comprising a pair of pressure chambers H and H', having flexible walls or diaphragms connected to the opposite ends of a lever H² the fulcrum H³ of which can be adjusted lengthwise of the lever by rotating the adjusting screw H⁴. The pressure chamber H is connected to the firebox by the pressure transmitting pipe H⁵ and the chamber H' is connected to the smoke box by the pressure transmitting pipe H⁶. The lever H² carries a needle valve H⁷ which regulates the leakage from a chamber I (see Fig. 2) through an outlet I⁴. A pipe I' connects the chamber I to the pressure motor G. A motive fluid such as compressed air is constantly supplied to the pipe I' through the supply connection I² which includes a restricted orifice I³.

With the arrangement described substantially all of the steam generated by the locomotive is discharged in normal operation through the exhaust nozzle B, and the ejector or draft producing effect of the latter is therefore approximately proportional to the rate of steam output from the locomotive boiler. The effect of the exhaust nozzle is to create a pressure less than that of the atmosphere in the firebox of the locomotive and a still lower pressure in the smoke box. The drop in pressure between the firebox and the smoke box is a function on the one hand of the volume of flow through the boiler tubes, and on the other hand, of the resistance of the boiler tubes to the flow through them. Similarly the drop in pressure between the atmosphere and the firebox is a function of the amount of gas flow through the fuel bed and the resistance of the fuel bed to the gas flow through it. If the fuel bed resistance to flow is constant, the difference between the pressure of the

atmosphere and the pressure in the fire box will vary in proportion to the difference between the pressure of the atmosphere and the pressure in the smoke box. Therefore,

- 5 if the fulcrum H^3 for the lever H^2 is nearer the center of chamber H' than to the center of the chamber H when the flexible walls of the two chambers are of the same size, or if the fulcrum is midway between the centers
- 10 of the two chambers, and the diaphragm of the chamber H' is smaller than the diaphragm of the chamber H , there will be a certain standard fuel bed resistance to flow which will maintain the lever H^2 in equilibrium regardless of whether the rate of combustion is slow or rapid. The resistance of the fuel bed to gas flow through it, required to maintain the lever H^2 in equilibrium, can be adjusted in the apparatus
- 15 shown, by adjusting the fulcrum block H^3 along the screw H^4 . The maintenance of a constant fuel bed resistance insures, and with the apparatus of Fig. 1 is necessary to secure, the proper influx of secondary air
- 20 through the inlet A^9 .
- 25

When the fuel bed resistance to flow becomes greater than the predetermined standard, the differential between the pressure of the atmosphere and that in the firebox increases relative to the differential between the pressure of the atmosphere and that in the smoke box, and this shifts the lever H^2 in the direction moving the needle valve H^7 farther into the orifice I^4 and thereby causes the pressure in the pipe I' and the chamber G to build up. This moves the valve F' in the closing direction, throttles the supply of steam to the stoker motor E' , reduces the rate of fuel supply to the grate and thereby brings about a reduction in fuel bed thickness and resistance. Conversely when the fuel bed resistance falls below the standard value, the lever H^2 is shifted to withdraw the needle valve H^7 somewhat, whereby the pressure in the pipe I' and chamber G is reduced, and the valve F' is correspondingly opened by the spring G' , thus speeding up the stoker motor and restoring the normal fuel bed thickness. In the apparatus of Fig. 1, the strong draft prevailing when the rate of combustion is high, tends to loosen up the fuel bed, and in consequence tends to the maintenance of a slightly thicker fuel bed when the rate of combustion is high than when the rate of combustion is low.

When the steam pressure falls below the normal, a valve L , connected to the stem of the valve D , and located in the live steam supply connection M to the live steam auxiliary draft creating nozzle N is opened, thus increasing the draft and tending to bring the steam pressure up to normal. The automatic control of the draft effected by the discharge through the exhaust nozzle B , and the pressure chamber C may be supple-

mented, if desired, by the auxiliary steam supply through the pipe K and manually controlled valve K' to the live steam draft nozzle N .

The specific form of the apparatus through which the differential pressure device controls the supply of fuel to the grate A' is not an essential feature of my invention; but a characteristic feature of my invention is the simplicity of the differential pressure device itself. While this device comprises but two pressure chambers, H and H' , it operates the fuel feeding mechanism as required to maintain a predetermined ratio between the pressure drop or draft loss in the fuel bed, and the pressure drop or draft loss between the smoke box A^2 and the fire box A^8 .

The effective use of this simple form of differential device as a fuel supply controller, requires that the furnace shall be open to the atmosphere, or connected thereto by a passage of constant flow resistance, at one end or the other of the draft path. In Fig. 1, the furnace is thus open to the atmosphere at the inlet end of the draft path, through the primary air inlet opening A^4 . The invention is not limited, however, to use in a furnace operating under induced draft with atmospheric pressure in the ash pit. It may be used equally well in a furnace discharging waste gases directly and freely into the atmosphere and having its ash pit air pressure above that of the atmosphere, as is the case, for example, in the furnace shown in Fig. 3.

In the typical stationary boiler furnace AA diagrammatically illustrated in Fig. 3, the draft creating device is a blower O delivering air under pressure to the furnace ash pit inlet A^{10} , and A^5 is the outlet pipe through which the waste gases are discharged to the atmosphere. Secondary air is supplied to the furnace chamber above the fuel bed from the ash pit through the bridge wall passage A^{20} which may be controlled by a damper A^{21} . Fuel is supplied to the furnace grate A' by a stoker EA operated by a steam motor EA' , and the action of the latter is controlled by a differential device comprising chambers H and H' exactly as the motor E' of Fig. 1 is controlled. In Fig. 3, however, H , the smaller of the two pressure chambers or the one closer to the lever fulcrum H^3 , is connected to the furnace ash pit, while the chamber H is connected to the furnace chamber immediately above the fuel bed as in Fig. 1. In the arrangement of Fig. 3, the difference between the pressures acting on the two sides of the flexible wall of the chamber H is the difference between the pressure in the ash pit and the pressure in the atmosphere and this pressure drop is the draft loss in the furnace from the top of the fuel bed to the waste gas outlet.

Similarly the differential to which the flexible wall of the chamber H' is subjected is equal to the sum of the draft loss in the fuel bed plus the draft loss from the top 5 of the fuel bed to the waste gas outlet. The apparatus of Fig. 3 thus acts to maintain a constant ratio between the draft loss in the fuel bed, and the draft loss through a portion of the furnace in which the flow 10 resistance is constant, and therefore tends to maintain a fuel bed of constant flow resistance.

In Fig. 3 the rate of combustion depends 15 on the speed of the blower O . The speed of the blower O can obviously be controlled manually, or can be automatically controlled in accordance with the rate of steam generation or the boiler steam pressure. As shown it is controlled in response to the steam pressure 20 by means comprising a pressure motor g connected by a pipe g' to the boiler steam main, and controlling a valve X' in the steam supply pipe X to the turbine or other steam motor driving the blower O . The pressure motor g increases or decreases the supply of steam to the motor driving the blower O , as the boiler steam pressure decreases or increases. The simple air and 25 fuel supply regulation illustrated in Fig. 3 is especially effective when a battery of boilers thus controlled deliver steam into the same steam main, as the regulating apparatus then serves not only to keep proper fuel beds in the varying furnaces, but also 30 to properly divide the load among the different boilers.

In each form of my invention illustrated, 35 the resultant of the forces acting on the lever H^2 whereby the latter is turned about its fulcrum as the fuel bed resistance changes, is proportional to the difference between the resultant of the pressure in the furnace above the grate and the opposing pressure 40 of the atmosphere acting over one area, and the resultant of the pressure in the furnace adjacent the draft creating device and the opposing pressure of the atmosphere acting over an area of different size. In the particular construction illustrated, the two opposing resultants referred to are directly obtained by the action of the furnace and opposing atmospheric pressures on the similarly sized flexible wall portions of the chambers H and H' , but on account of the unequal distances between the fulcrum of the 45 lever H^2 and the points of connection of the lever to the flexible walls of the pressure chambers H and H' , the same effect is obtained as would be had if the flexible walls 50 of the two pressure chambers were of unequal size but with each acting with the same leverage on the lever H^2 . The effect of adjusting the fulcrum axis in the particular construction illustrated, is the same as would 55 be obtained by changing the relative sizes

of the flexible wall portions of the chambers H and H' without changing the leverage with which they act on the lever H^2 .

While in accordance with the provisions of the statutes I have illustrated and described the best forms of my invention now known to me, it will be apparent to those skilled in the art that many changes may be made in the forms of the apparatus and modes of operation described without departing from the spirit of my invention as set forth in the appended claims. Certain novel features disclosed but not claimed herein are claimed in my application, Serial No 418,087, filed October 19, 1920, of which this application is in part a continuation.

Having now described my invention, what I claim as new and desire to secure by Letters Patent, is:

1. The combination with a furnace comprising a grate on which solid fuel is burned and having its primary air inlet and its outlet for gaseous products of combustion connected, one to the atmosphere by a passage of constant flow resistance, and the other to a draft creating device, of fuel supply means automatically responsive to a force proportional to the difference between the resultant of the pressure in the furnace above the grate and the opposing pressure of the atmosphere over one area, and the resultant of the pressure in the furnace adjacent the draft creating device and the opposing pressure of the atmosphere over an area different from the first mentioned area, for supplying fuel to said grate as required to maintain a fuel bed of approximately constant resistance to gas flow therethrough.

2. The combination with a furnace comprising a grate on which solid fuel is burned, and having its primary air inlet and its outlet for gaseous products of combustion connected, one to the atmosphere by a passage of constant flow resistance, and the other to a draft creating device, of a differential pressure device comprising two pressure chambers each having a movable wall portion exposed externally to atmospheric pressure, a connection between the interior of one pressure chamber and the furnace interior immediately above the grate, and a connection between the other pressure chamber and the furnace interior adjacent the connection of the latter to the draft creating device, and fuel supply means automatically controlled by the resultant of the internal and external forces acting on said movable wall portions for supplying fuel to said grate as required to maintain an approximately constant ratio between the draft loss in the fuel bed and the draft loss in a portion of the furnace in which the flow resistance is constant.

3. The combination with a furnace com-

- 4
- prising a grate on which solid fuel is burned and having its primary air inlet and its outlet for gaseous products of combustion connected, one to the atmosphere by a passage 5 of constant flow resistance, and having an adjustable secondary air inlet, and the other to a draft creating device, fuel supply means automatically responsive to a force proportional to the difference between the resultant of the pressure in the furnace above the grate and the opposing pressure 10 of the atmosphere over one area, and the resultant of the pressure in the furnace adjacent the draft creating device and the opposing pressure 15 of the atmosphere over an area different from the first mentioned area, for supplying fuel to said grate as required to maintain a fuel bed of approximately constant resistance to gas flow therethrough.
- 10 4. The combination with a furnace comprising a grate on which solid fuel is burned and having its primary air inlet and its outlet for gaseous products of combustion connected, one to the atmosphere by a passage 20 of constant flow resistance, and having an adjustable secondary air inlet, and the other to a draft creating device, fuel supply means automatically responsive to a force proportional to the difference between the resultant of the pressure in the furnace above the grate and the opposing pressure 25 of the atmosphere over one area, and the resultant of the pressure in the furnace adjacent the draft creating device and the opposing pressure 30 of the atmosphere over an area of adjustable size, for supplying fuel to said grate as required to maintain a fuel bed of approximately constant resistance to gas flow therethrough.

Signed at New York in the county of New York and State of New York this 19th day of August A. D. 1922.

GEORGE H. GIBSON.
